UNITED STATES PATENT OFFICE.

HERBERT B. TAYLOR, OF ROCHESTER, NEW YORK, ASSIGNOR TO GENERAL RAILWAY SIGNAL COMPANY, OF ROCHESTER, NEW YORK.

SKATE MACHINE.

Application filed November 30, 1925. Serial No. 72,264.

This invention relates to an emergency stop device for stopping railway cars or trains, and more particularly to means for moving such stop device from its inactive to 5 its active position, and vice versa.

In railway signaling practice it is quite customary to provide a derail, that is, means for derailing a train, at some distance in the rear of an interlocking point, usually a 10 crossing, for the purpose of providing emergency stopping means for stopping a train, it being considered preferable to derail a train rather than have it run in front of a fast moving train on an intersecting 15 track. Also, this is the case in classification systems, where cars are reclassified into new trains, usually by accelerating individual or groups of cars by running them off of a hump, through suitable switches and 20 into the proper classification track, after which they are retarded to a low speed by suitable car retarders or track brakes. In the event the track brakes in such classification system do not work properly, or the 25 operator has failed to place them in their active braking position, such cars will run into other cars on the classification track at excessive and dangerous speeds which may cause injury to them and their lading, and 30 to avoid this it has been the practice to place a skate on the track ahead of such car onto which the car may ride and be retarded by the sliding of the first wheels and axle thereof. In accordance with the present invention 35 it is proposed to provide power operating mechanism for not only placing such skate or derail in its active position on the rail, but also for rendering it capable of again removing such derail or skate from 40 the rail to its inactive position.

More specifically, particularly when the invention is applied to a skate operating mechanism, it is proposed to detachably connect the skate to the skate placing mechanism in a manner so that endwise movement 45 of the skate in one general direction only permits disengagement of the skate from the skate placing mechanism, this being accomplished by a mechanical detachable connection or magnetic attraction between the various parts thereof. Other characteristic 50 features of the invention reside in the provision of adjustable connections so as to avoid variation of the normal and ultimate posi-

tion of the stop device, and in the provision 55 of suitable motor operated mechanism for moving the emergency stop device from one to the other of its two positions.

Other objects, purposes and characteristic 60 features of the invention will appear as the description thereof progresses, and certain detail features of the invention may be ascertained from the drawings.

In describing this invention in detail reference will be made to the accompanying 65 drawings in which:—

Fig. 1 is a plan view of an embodiment of the invention, showing part of the mechanism casing for the power operated mechanism broken away to illustrate the contact 70 mechanism;

Fig. 2 is a sectional elevation, on line 2—2 of Fig. 1, of the pivoted skate placing mechanism showing the skate detachably connected thereto; 75

Fig. 3 is a view similar to Fig. 2 with the skate in its active, instead of its inactive position;

Fig. 4 is a side elevation of the apparatus shown in Fig. 2, with the skate removed 80 and as viewed in the direction of the arrows on line 4—4;

Fig. 5 is a sectional elevation taken through the rail and shaft on the line 5—5 of Fig. 1 as viewed in the direction of the 85 arrows, particularly illustrating the manner in which the return spring is anchored;

Fig. 6 is a plan view of the mechanism casing containing the mechanism for operating the skate placing mechanism taken on the line 6—6 of Fig. 7, showing a part of the right hand end of the casing broken away, and showing the cover removed; 90

Fig. 7 is a sectional elevation taken on the line 7—7 of Fig. 6 as viewed in the direction of the arrows; 95

Fig. 8 is a sectional elevation taken on the line 8—8 of Fig. 7 as viewed in the direction of the arrows, and particularly illustrating how the bifurcated throw rod straddles the 100 main journal block of the mechanism casing;

Fig. 9 is a sectional elevation taken on the line 9—9 of Fig. 7 illustrating the guide for the throw bar; 105

Fig. 10 illustrates the control circuit for the skate machine shown in Figs. 1 to 9;

Fig. 11 is a modified form of skate con-

trolling means in which the skate is held magnetically;

Fig. 12 is an end elevation of the apparatus shown in Fig. 11; and

5 Fig. 13 illustrates a modified form of construction in which the circuit controller of the skate machine is operated at an earlier point in its cycle of operation than is the mechanism shown in Figs. 1 to 10.

10 Although the present invention relates to emergency car stopping means of either the skate or derail type, it has been considered expedient to limit the drawings to apparatus for placing a skate into its active or inactive position, it of course being understood that a derail is placed upon the rail in the same way as is a skate, and that the specific illustration of a derail is deemed unnecessary and superfluous.

20 In providing means for placing a skate, such as the skate S illustrated in Fig. 1, on a rail it is preferable to have a skate placing mechanism definitely located with respect to such rail; and in accordance with the present invention the main support 1 of the skate placing mechanism is bolted by hook bolts 2, directly to the track rail 3, shown supported by ties 4. This main support 1 has two upstanding lugs 1^a which are cross drilled to provide journals for the shaft 5. On the shaft 5 is pivoted the skate placing arm 7 having sockets 7^a on the ends thereof for the purpose of housing spring pressed plungers 8 more particularly described hereinafter. The skate placing arm 7 is pivotally supported on the shaft 5 but may be adjustably secured thereto by the operating arm 10 pinned to the shaft 5 by pins 11, the free end of this arm being adjustably connected to the skate placing member 7 by the cap screws 9 and 12. Referring to Fig. 4 it is noted that the two adjusting screws 12 are threaded into the arm 10, but that the cap screw 9 is threaded into the skate throwing member 7 and has its end bearing against the arm 10. It is thus noted that the skate placing arm 7 is fixedly but adjustably connected to the shaft 5.

50 The skate S which is of the general shape shown, has its forward end bifurcated and in the bifurcation is pivotally supported a roller 15 on a pin 16. In the lower face of the flange projecting from this skate is contained a tapered mortise or socketed groove into which a correspondingly shaped flaring tenon or tongue 17 secured in the skate placing arm 7 is adapted to engage so as to form a tapered dove-tailed connection, whereby the skate is freely slid off 55 of the tongue 17 in that direction in which the skate is moved when engaged by a car wheel moving in the normal direction of traffic. The ends of this tenon or tongue 17 have plungers 8 associated therewith in which 60 are fastened bolts 18 passing through the

spring chambers 7^a, springs 19 being contained in these chambers so as to force the tenon 17 upward when the skate is in its active position, adjustment of the extreme height of the tenon 17 being afforded by the nuts 16. With the skate placing mechanism in its normal inactive position the skate S may rest on a support comprising a piece of strap iron 20 bolted to the ties 4 by lag screws 21, this strap iron piece 20 having 75 cap screws 22 locked by lock nuts 23 threaded therein to form an adjustable stop on which the skate S is adapted to rest when in its inactive position. By this construction, the mechanism may be adjusted so that the skate just rests on the track rail when in its active position and if then moved to its inactive position partially rests on the adjustable stop screws 22 if these screws are 80 properly adjusted.

85 Referring to Fig. 4 it should be noted that this view illustrates the taper of the key or tenon 17 converging in the direction of traffic, the direction of traffic being from right to left in the view shown in Fig. 4 90 whereas traffic is from left to right in the view shown in Fig. 1 as indicated by the arrows.

95 Referring now particularly to Figs. 1, 6 and 7 the motive power or operating mechanism of the skate machine is contained in a mechanism casing 30 of the shape as shown in the drawings, having a motor 29 bolted to one end thereof the commutator of which is accessible through the cover 31 hinged at 32, which cover is held closed by the hasp fastener 33, the main opening of the casing 30 being covered by the main cover 35 hinged at 36 and held closed by a hasp fastener 37. This cover 35 is provided with a groove adjacent its periphery in which groove is contained a gasket 38. The cover 35 also has fastened to its inside face, but spaced a short distance therefrom, a supplemental drip cover for shielding the mechanism from 105 drops of water condensing under the main cover and dripping off.

110 Projecting up from the bottom wall of the casing 30 is a journal block 30^a in which is fixedly secured by the pin 40 a spindle 41. 115 On this stationary spindle 41 is journaled the main bevel gear 42 from the bottom face of which project parallelly arranged spiral flanges 42^a between which the roller 43 supported by journal pin 44 riveted in the throw bar 45 is positioned. This throw bar 45 has one of its ends bifurcated as shown in dotted lines in Fig. 6, and the bifurcation straddles the journal block 30^a (see Fig. 8), and has its other end guided in the cut-away portions of lugs 30^b projected up from the bottom wall of the casing, and is held down by plates 48 fastened down by long headed cap screws 49, as shown.

120 This main cam gear 42 is driven by a bev-

eled pinion 52 frictionally fastened to the shaft 53 of the motor 29 by friction washers 54 pressed against the pinion by the compression spring 55 held in place by nuts 56 through the medium of washers 57 and 58 keyed to the shaft 53. To the throw bar 45 is riveted a bifurcated pedestal 60 between the bifurcations of which is pivoted a link 61 by a pin 62 having its other end 10 pivotally connected between the bifurcated crank 63 fastened to the shaft 64 journaled in the casing 30. The shafts 64 and 5 are operatively but detachably connected by the universal joints 66, 67 and the shaft 69, the 15 universal joint 67 including a socket member 68 having a square hole therein in which the square shaft 69 extends. From this construction it appears, referring particularly to Fig. 6, that if the main gear 42 is rotated 20 in a clockwise direction the roller 43 guided between flanges 42^a is caused to move from right to left to place the skate S into its inactive position, and that the main gear is permitted to rotate substantially a complete 25 revolution. It is thus noted that a flexible operating connection exists between the mechanism casing and the skate placing mechanism which permits ready detachment, and which allows the skate and the skate 30 placing mechanism to be dragged away in case of accident, such as derailment, without injuring the mechanism casing and the mechanism contained therein.

Referring to Figs. 1 and 7 the top portion 35 of the stationary spindle 41 is squared and has fastened thereon a contact supporting plate 70 which carries insulating blocks 71 and 72 on which are mounted stationary pairs of contacts 73, 74, 75, and 76, which 40 pairs of contacts are adapted to be bridged by contact segments 77 and 78 supported by the movable contact carrier 79 through the medium of insulating blocks 80. From the bottom side of the contact carrier 79 projects a lug 82 which is adapted to be engaged by the lug 42^b projecting up from the main beveled gear 42. It is thus noted that if the gear 42 is rotated in a clockwise direction 45 from the position shown in Fig. 6 through a complete revolution, the contact carrier 79 is moved from a position where it bridges the two pairs of contacts 73 and 74 to a position wherein it bridges the pairs of contacts 75 and 76 just before the gear has completed a complete revolution to thus constitute a lost motion connection between the gear and contact carrier. This lost motion connection between the gear 42 and the contact carrier 79 causes the contact carrier 79 50 to be operated just before the motor driving the gear 42 has completed its cycle, and in so doing establishes a circuit for operating the motor in the opposite direction. Incidentally, this change in the connections of the motor also establishes a snubbing circuit 55 whereby the motor is braked due to generation of current by its armature due to the inertia of the motor as more particularly pointed out hereinafter.

Referring to Fig. 10, the motor circuit 60 is shown with the skate machine in its abnormal position, that is, in the same position as it is in Figs. 6 and 7, wherein the skate is on the track rail 3, but in the opposite position from that shown in Fig. 1. If the lever L for controlling the skate machine, which is preferably located in a tower a considerable distance from the skate machine, is now moved toward the normal position (the position for operating the motor 65 to remove the skate from the track rail) the contacts 85 and 86 will assume the dotted position, under which condition the following circuit is completed for operating the motor:—beginning at the battery B, wires 70 87 and 88, contact 85 in its dotted position, wire 89, contacts 74—77, wires 90 and 91, armature 92 of the motor 29, wire 93, contacts 73—78, wires 94 and 95, field winding 96, wires 97 and 98, back to the battery B. 75 This causes the motor to operate the main cam gear 42 in a clockwise direction, thus moving the throw bar from right to left (from the position shown in Fig. 7) and moving the skate into its normal inactive 80 position (as shown in Figs. 1 and 2). When the motor has almost completed its stroke the lug 42^b engages the lug 82, thereby moving the contact carrier 79 to the dotted position (see Fig. 10) and thereby establishes 85 a snubbing circuit in which the armature connections are reversed, so that the voltage generated in the armature causes current to flow in the field winding 96, in the same direction as it flowed when operating as a motor, thus resulting in a series generator short circuited through the contact 86. This snubbing circuit may be traced as follows:—beginning at the armature 92, wire 91, contacts 75—75, wires 104 and 95, field winding 96, wires 97, 103 and 102, contact 86 in the dotted position, wire 101, contacts 76—76, wires 100 and 93, back to armature 92. With this snubbing circuit completed and the motor operating due to inertia, current 90 is generated in the motor connected to constitute a short circuited series generator, which stops the mechanism very quickly. It should be noted that the direction of current flow in the armature has been reversed 95 whereas the direction of current flow in the field is the same.

In addition to this snubbing or dynamic braking action of the motor, when it has almost completed its cycle of operation, there 100 is provided a mechanical snub, so to speak, which consists of a multiple plate disk friction slip clutch or brake C, the housing 105 of which is mounted on the long headed cap screws 49, and in which housing is pivotally 110

secured a shaft 106 having its main portion squared, having mounted the movable plates 107 thereon and between which plates 107 are contained stationary plates 108, held in place by cap screws 109. The shaft 106 projects through the bottom of this casing C and has pinned thereto an arm 110 which is adapted to be engaged by the pin 111 riveted into and projecting from the upper face of the main gear 42. It is thus noted that at the end of each cycle of operation the mechanism engages and is stopped by the arm 110. This combined electrical and mechanical snubbing construction causes the mechanism to be braked both electrically and mechanically when it has almost reached the end of its operating cycle, and it is desired to be understood that either of these expedients may be made used separately, if desired, or both may be used in the same machine, as illustrated.

If now the skate is moved into its active position (by throwing switch L from its dotted line position to its full line position, 25 to thereby complete a circuit through the armature 92 and the field 96 of the motor, traceable from B, 87, 86, 101, 76—77, 100, 93, 92, 91, 75—78, 104, 95, 96, 97 and back to B, to operate the gear 42 motor clockwise) as 30 shown in Figs. 3 and 7 and a car moving from left to right viewing the apparatus as shown in Fig. 1 engages the skate, the first wheel of the car rides upon the nose of the skate S possibly tilting or depressing the 35 skate to a certain extent, but in so doing the skate cannot rest entirely on the key or tongue 17, because this tongue may be depressed in opposition to the force of compression springs 19. In other words, the 40 skate is free to be tilted toward the left (see Fig. 3) without causing excessive friction to exist between the groove in the skate and the tongue or tenon 17. Since this tongue is tapered as shown in Fig. 4, sliding of the 45 skate causes the fit between the tenon and the socket or groove to become more loose, so that the skate is readily disengaged from its holder as it is slid along the rail. This 50 feature is of particular importance, because if binding should take place between the skate and its holder the apparatus would probably be torn away from the rail. In the event that the connection between the skate and its holder should be jammed and be 55 broken away from the rail, the casing containing the operating mechanism would probably not be damaged, by reason of the slideable connection existing between socket member 68 and square shaft 69.

60 Since the skate is rather heavy, it has been found expedient to provide spring means acting in opposition to gravity acting on the skate S. In the particular construction shown, a hook shaped lug 114, having a 65 square socket, is contained on the square

shaft 69, and a double coil spring 115 has its middle looped portion engaging this hook, which spring 115 has each of its free ends bent in the form of a hook engaging the bottom flange of the rail (see Fig. 5). 70 The provision of this spring construction reduces the power necessary to move the skate from its inactive to its active position to such an extent that a much smaller motor is required for operating the same. 75

Modification.—Instead of providing a tapered dove-tailed connection between the skate and its holder, another form of the invention contemplates the provision of an electro-magnet which may or may not have permanent magnet characteristics. Referring to Fig. 11 the skate holder comprises an operating arm 120 which is pinned to the shaft 5 by pins 121. This arm 120 has a U-shaped core 122 secured thereto on which is contained a coil 123. The magnetic characteristic of the core 122 may be such as to constitute it a permanent magnet, or this core may be constructed of soft iron either laminated or not laminated. The coil 123 90 is connected in series with the field winding 96 of the operating motor, so that whenever current flows in this field winding current also flows in the coil 123. It should be noted that the current flowing in the field winding 95 96 is never reversed, so that the residual magnetism set up in the core 122 is always in the same direction.

The skate which is preferably made of a good quality of magnetic material in practice is placed in position on the U-shaped core 122, and in the preferred construction the residual magnetism of the core 122 is sufficient to hold the skate when in either its inactive or its active position, and with the provision of the coil 123 which, of course, is energized while the skate machine is being operated and while the skate is being moved, sufficient magnetism is present to lift the skate from one to the other of its extreme positions. In this modified construction, the dimensions are preferably so chosen that the engagement of a wheel with the skate will tend to lift the flange which is in engagement with the core 122 away from the core; in any event, the only connection existing between the skate and its holder is that due to magnetic attraction, and no binding action can possibly take place between the skate and its holder as the skate is slid away by a passing car. The circuit arrangement for this modified form of the invention as shown in Fig. 11 is the same as the one heretofore described and shown in Fig. 10 except that the field winding has the coil 123 connected in series therewith. 115 120 125

Modified circuit controller.—In the arrangement shown in Figs. 1 to 10, only a very short distance of movement of the gear 130

42 is possible after the circuit controller has been reversed and the snubbing circuit has been completed. In other words, the amount of movement during which dynamic braking 5 is effected is extremely small because the reversing switch is not operated until the gear 42 has practically completed its revolution. In Fig. 13 has been shown an arrangement 10 in which a lost motion mechanism is employed for reversing the circuit controller an appreciable time period before the gear 42 has completed its cycle of operation. Instead of the lug 42^b projecting up from the gear 42, the modified construction employs 15 a lug 42^c having an arcuate hole therein in which is contained the plunger 130. This plunger 130 is provided with two notches into which the ball 131 depressed by a spring 132 is adapted to engage, this spring 132 being 20 retained in position by a pin 133. Also, this modified construction includes lugs 79^a projecting from the contact carrier 79, which lugs are adapted to engage a stop pin 135 secured in the stationary plate of the 25 stationary contact carrier 70. In operating the skate machine, when this modified form of circuit controller shown in Fig. 13 is employed, the rotation of the gear 42, which is always in the opposite direction from 30 which it was rotated previously, causes the arcuate plunger 130 to have its furthest projecting end strike the lug 82 depending from the contact carrier 79, and thereby causes the contact carrier 79 to be operated earlier in 35 the cycle of operation, thus establishing a snubbing circuit proportionately earlier in the operating cycle. After the contact carrier 79 has been operated to its opposite position whereupon it is limited by the stops 40 79^a—135 further movement of the gear 42 causes the arcuate plunger to be shifted in the lug 42^c to such an extent that the ball 131 engages the other notch in this plunger 130. In other words, the construction shown 45 in Fig. 13 causes the circuit controller to be operated and in addition allows a certain amount of movement of the gear 42 after this circuit controller has been operated without further operating this circuit controller, so that more time is allowed for the 50 motor to be electrically braked.

Having thus shown several forms of the present invention, and having illustrated and described them rather specifically, it is 55 desired to be understood that this has been done for the purpose of clearly disclosing the invention rather than illustrating the exact construction preferably employed in practicing the invention or its scope, and that various changes and modifications may be made to adapt the invention to the particular problems encountered in practice such as the source of power available and other local conditions, and whether the invention 60 is to be used for operating a skate or a de-

rail, all without departing from the scope of the invention or the idea of means underlying the same.

What I claim as new is:—

1. In an emergency train stop device, in combination, a motor driven cam, a throw bar adapted to be reciprocated by said cam, automatically operated means associated with said motor for causing the electrical power to be cut off from said motor when it has almost completed its operating stroke, and a train stop block operatively connected to said throw bar in a manner to cause it to be placed in an active position on the rail of a railway track when the throw bar is operated in one direction. 70

2. In an emergency train stop device, in combination, a motor driven cam, a throw bar adapted to be reciprocated by said cam, automatically operated means associated with said motor for causing the electrical power to be cut off from said motor when it has almost completed its operating stroke, a train stop block operatively connected to said throw bar in a manner to cause it to be placed in an active position on the rail of a railway track when the throw bar is operated in one direction, and means for retarding the motor when it has almost completed its operating stroke. 85

3. In an emergency train stop device, in combination, a motor driven cam, a throw bar adapted to be reciprocated by said cam, automatically operated means associated with said motor for causing the electrical power to be cut off from said motor and for establishing a snubbing circuit for stopping said motor when it has almost completed its operating stroke, and a train stop block operatively connected to said throw bar in a manner to cause it to be placed in an active position on the rail of a railway track when the throw bar is operated in one direction. 95

4. In an emergency train stop device, in combination, a motor driven cam, a throw bar adapted to be reciprocated by said cam, automatically operated means associated with said motor for causing the electrical power to be cut off from said motor when it has almost completed its operating stroke, and a train stop block operatively connected to said throw bar in a manner to cause it to be placed in an active position on the rail of a railway track when the throw bar is operated in one direction, means for retarding the motor when it has almost completed its operating stroke and friction braking means effective only through a part of the cycle of operation of said cam for stopping the motor when it has completed its operating stroke. 110

5. In an emergency railway skate placing mechanism, the combination with a casing, of a main gear in said casing, a motor out- 125

side, and bolted to an open end, of said casing, and having a pinion on its shaft arranged to enter said casing and operatively engage said main gear when the motor is bolted in position, a throw bar in said casing operatively connected to said main gear, a support detachably and securely fastened to a rail of a railway track, and means pivotally supported in said support adapted to carry a skate and operatively connected to said throw bar.

6. In an emergency train stop placing mechanism, the combination with a casing, of a main gear in said casing, a motor bolted to an open end of said casing having a pinion on its shaft arranged to operatively engage said main gear when the motor is bolted in position, a throw bar in said casing operatively connected to said main gear, a support securely fastened to the rail of a railway track, means pivotally supported in said support adapted to carry a train stop block and operatively connected to said throw bar, and means for establishing a regenerative braking circuit for said motor when said mechanism has almost completed its operating cycle.

7. In an emergency train stop placing mechanism, the combination with a casing, of a main gear in said casing, a motor bolted to an open end of said casing having a pinion on its shaft arranged to operatively engage said main gear when the motor is bolted in position, a throw bar in said casing operatively connected to said main gear, a support securely fastened to the rail of a railway track, means pivotally supported in said support adapted to carry a train stop block and operatively connected to said throw bar, and means for establishing regenerative braking and mechanical braking when the mechanism has almost completed its operating cycle.

8. In an emergency train stop placing mechanism, the combination with a casing, of a main gear in said casing, a motor bolted to an open end of said casing having a pinion on its shaft arranged to operatively engage said main gear when the motor is bolted in position, a throw bar in said casing operatively connected to said main gear, a support securely fastened to the rail of a railway track, means pivotally supported in said support adapted to carry a train stop block and operatively connected to said throw bar, and means for establishing a regenerative braking circuit for said motor when said mechanism has almost completed its operating cycle, including a circuit controller operated by yieldable means projecting from said main gear.

9. In an emergency train stop placing mechanism, the combination with a casing, of a main gear in said casing, a motor bolted to an open end of said casing having

a pinion on its shaft arranged to operatively engage said gear when the motor is bolted in position, a throw bar in said casing operatively connected to said main gear, a support securely fastened to the rail of a railway track, means pivotally supported in said support adapted to carry a train stop block and operatively connected to said throw bar, and means for establishing a regenerative braking circuit for said motor when said mechanism has almost completed its operating cycle, including a circuit controller operated by lost motion mechanism associated with said main gear.

10. In an emergency train stop device, the combination with a railway rail, of a support fixedly secured to said rail, a skate placing mechanism pivotally connected to said support having one element of a slidably detachable connecting means associated therewith in a manner to support said element yieldably with respect to said support, and a skate adapted to fit on the rail and skid the first wheels and axle of a passing car having the other element of said detachable connecting means associated therewith.

11. In an emergency train stop device, the combination with a railway rail, of a support fixedly secured to said rail, a skate placing mechanism pivotally connected to said support having one element of a slidable detachable connecting means associated therewith, a skate adapted to fit on the rail and skid the first wheels and axle of a passing car and shaped to form the counter part portion of said one element of said detachable connecting means, and spring means for aiding said operating means in operating said skate placing mechanism through a certain part of its operating cycle.

12. In an emergency train stop device, the combination with a railway rail, of a support fixedly secured to said rail, a skate placing mechanism pivotally connected to said support and having one element of a slidably longitudinally tapered detachable connecting means associated therewith, a skate adapted to fit on the rail and skid the first wheels and axle of a passing car and having the other element of said detachable connecting means associated therewith whereby said skate can be slid relatively to said mechanism in one direction only, and electrically operated means for operating said skate placing mechanism to move said skate from one to the other of its active and inactive positions.

13. In an emergency train stop device, the combination with a railway rail, of a support fixedly secured to said rail, a skate placing mechanism pivotally connected to said support having one element of a slidably detachable connecting means associated therewith, a skate adapted to fit on the rail and skid the first wheels and axle of a pass-

- ing car and having the other element of said detachable connecting means associated therewith, electrically operated means for operating said skate placing mechanism to move said skate from one to the other of its active and inactive positions, and a friction brake rendered active when the mechanism has almost completed its operating cycle.
14. In an emergency train stop device, the combination with a railway rail, of a support fixedly secured to said rail, a skate placing mechanism pivotally connected to said support having one element of a slideable detachable connecting means associated therewith, a skate adapted to fit on the rail and skid the first wheels and axle of a passing car and having the other element of said detachable connecting means associated therewith, and an electric motor for operating said skate placing mechanism to move said skate from one to the other of its active and inactive positions, and means for completing a regenerative braking circuit for said motor when said mechanism has almost completed its operating cycle.
15. In an emergency train stop device, the combination with a railway rail, of a support fixedly secured to said rail, a skate placing mechanism pivotally connected to said support having one element of a slideable detachable connecting means associated therewith, a skate adapted to fit on the rail and skid the first wheels and axle of a passing car and having a portion shaped to constitute the other element of said detachable connecting means, an electric motor for operating said skate placing mechanism to move said skate from one to the other of its active and inactive positions, and combined dynamic and friction braking means rendered active when the mechanism has almost completed its operating cycle.
16. In an emergency train stop device, in combination, a motor driven member, automatically operated means associated with the motor for causing the electrical power to be cut off from the motor when it has almost completed its operating stroke and a train stop block operatively connected to said member in a manner to cause it to be placed in an active position on the rail of a railway track when the member is operated in one direction, and lost motion means to establish braking of the motor when it has almost completed its operative cycle.
17. In an emergency train stop device, in combination, a motor driven member, automatically operated means associated with the motor for causing the electrical power to be cut off from the motor when it has almost completed its operating stroke and a train stop block operatively connected to said member in a manner to cause it to be placed in an active position on the rail of a railway track when the member is operated in one direction, and lost motion means to establish regenerative braking of the motor when it has almost completed its operative cycle.
18. In an emergency train stop device, the combination with a railway rail, of a support fixedly secured to said rail, a skate placing mechanism pivotally connected to said support and having one element of a slideably detachable connecting means associated therewith, means resiliently mounting said one element on said mechanism, and a skate adapted to fit on the rail and skid the first wheels and axle of a passing car having the other element of said detachable connecting means associated therewith.
19. In an emergency train stop device, the combination with a railway rail, of a support fixedly secured to said rail, a skate placing mechanism pivotally connected to said support having one element of a slideably detachable connecting means carried on spring pressed plungers carried by said skate placing mechanism, and a skate adapted to fit on the rail and skid the first wheels and axle of a passing car having the other element of said detachable connecting means associated therewith.
20. In an emergency train stop device, a support adapted to be fixed relative to a track rail, a skate placing mechanism pivoted to the support and having one element of a slideably detachable connection, and a track skate having the other element of the detachable connection and carried by said mechanism, the detachable connection including an undercut, longitudinally tapered grooved portion and a matching, dovetailed, longitudinally tapered, rib.

In testimony whereof I affix my signature.
HERBERT B. TAYLOR.
